STEPHEN N. BUCHANAN, OF NEW YORK, N. Y., ASSIGNOR TO THOMAS & BETTS CO., OF ELIZABETH, NEW JERSEY, A CORPORATION OF NEW JERSEY.

ELECTRIC-FIXTURE HANGER.

Application filed March 10, 1927. Serial No. 174,290.

This application relates to means for supporting electric light fixtures from the ceiling or walls of a room. It is the principal object of my invention to provide an electric fixture hanger, which is very cheap to manufacture and one which can be quickly assembled and installed in position.

My invention will be readily understood by a reading of this specification taken in connection with the annexed drawing, wherein Figure 1 illustrates one form of the device shown in operative position ready to receive the electric fixture.

Figure 2 is a view similar to Figure 1 showing a somewhat modified form.

Figure 3 is a view of the fixture hanger per se looking at the top of Figure 1.

Figure 4 is an end view looking at the left hand end of Figure 3.

Figure 5 is a view of an anchor member such as may be used in Figures 1 and 2, but having its ends bent. Figure 6 is a view similar to Figure 3 but with the ends of the anchor member formed to be in substantial alignment.

In the different views, 1 and 2, illustrates the arms of what I term the anchor member. The arms 1 and 2 are connected by an integral central portion 3, on which is movably or pivotally mounted an attachment member 4, to which the fixture or some fitting connected with the fixture is attached by means of the threads on the member 4. The anchor member and the attachment member 4 are first assembled by passing one end of the anchor member, which is preferably a piece of relatively large steel wire through a transverse hole at one end of the member 4, and then bending the ends of the wire by a suitable machine, or fixture into the position shown in Figure 3. For the purpose of positioning the fixture hanger in position, a wire 12 is passed through the hollow portion of the member 4 around the central part 3 and the ends brought down about as illustrated in Figure 3. With the parts in the position as shown in Figure 3, the hanger is then passed through a hole in the ceiling or wall and the arms 1 and 2 are allowed to tilt over and a

pull on the wire 12 will turn the member 4 to the position shown in Figures 1 and 2, after which one strand of the wire 12 is cut and the wire withdrawn, after which the outlet

box 5 is put in position and locked there by any suitable means such as a nut 6.

As shown in Figures 1 and 2, the arms of the anchor rest against the plaster 8 held by the laths 7, the finished plaster being illustrated by the portion 9.

To accommodate an arrangement as shown in Figure 2 the arms 1 and 2 may be bent as at 10 and 11 to take up for differences in thickness of the ceiling etc.

In the form of anchor member shown in Figure 5 the arms 1 and 2 have their ends 14 and 13 respectively bent in a manner so as to prevent turning or tipping of the anchor member. As shown in Figure 5, the ends 13 and 14 are bent substantially at right angles to their respective arms, and preferably lie in the same plane. It is to be understood that the bent ends 13 and 14 may be used in connection with the anchor member shown in either Figure 1 or 2.

In Figure 6 the anchor member has its ends 15 and 16 formed so that they lie substantially in alignment and when the attachment member 4 is in the position shown in Figure 6, which is the position for insertion through the hole in the wall or ceiling. The ends 15 and 16 and attachment member 4 have substantially the same axis.

It is to be understood that the form of the ends shown in Figure 6 may be used in connection with either of the anchor members shown in Figures 1 and 2.

By making the anchor member out of one piece of relatively large size wire of the required stiffness a one piece anchor member is obtained by merely cutting it off from a reel of wire thereby giving an anchor member that is very cheap to manufacture but one which will perform all the functions of the prior art devices which have been heretofore suggested in the way of punched and formed members.

Having thus described my invention, what I claim is:

1. A device of the class described consisting of a one-piece anchor member of relatively heavy wire having a central portion and two arms projecting in opposite directions from the central portion, said arms being disposed in different offset planes, and an attachment member pivotally carried by said central portion.

2. A device of the class described consisting of, an attachment member having a transverse hole at one end and an anchor of relatively heavy wire adapted to be passed through said transverse hole to about the central portion of the wire and then bent into arms on opposite sides of the attachment member in opposite directions, thereby leaving a central integral portion substantially at right angles to said arms and carrying the attachment member as described. 40
5. A device of the class described consisting of, a one piece anchor member having a central portion and two arms projecting in opposite directions from the central portion, said arms being disposed in different offset planes and adapted to have their ends bent to compensate for varying thicknesses of walls or ceilings and an attachment member 45 pivotally carried by said central portion. 50
10. A device of the class described consisting of, a one piece anchor member having a central portion and two arms projecting in opposite directions from the central portion, said arms being disposed in different offset planes parallel to the plane of the wall or ceiling, and having their ends bent so as to be in substantial alignment and an attachment member pivotally carried by said central portion. 55
15. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling, and having their ends bent to prevent turning of the anchor member and an attachment member pivotally carried by said central portion. 60
20. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling, and having their ends bent to compensate for varying thicknesses of walls or ceilings, said arms also having their ends adapted to be bent to prevent turning of the anchor member and an attachment member pivotally carried by said central portion. 65
25. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling and having their ends bent in opposite 70
30. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling and having their ends bent in opposite 75
35. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling and having their ends bent in opposite
- directions but in substantially the same plane 40 and an attachment member pivotally carried by said central portion.
6. A device for supporting a fixture in a wall or ceiling, comprising an anchor consisting of, a one piece anchor member having a central portion and two arms projecting in opposite directions from the central portion, said arms being disposed in different offset planes parallel to the plane of the wall or ceiling, and having their ends bent so as to be in substantial alignment and an attachment member pivotally carried by said central portion. 45
7. A device for supporting a fixture in a wall or ceiling consisting of, a one piece anchor member having a central portion and two arms projecting in opposite directions from the central portion, said arms being disposed in different offset planes and having a cross-sectional form such that their ends 50 may be easily bent to compensate for varying thicknesses of walls or ceilings, said arms also having their ends adapted to be bent to prevent turning of the anchor member and an attachment member pivotally carried by said central portion. 55
8. A device of the class described consisting of an attachment member having a transverse hole and an anchor of relatively heavy wire adapted to be passed through said transverse hole and then bent into arms on opposite sides of the attachment member thereby leaving a central integral portion substantially at right angles to said arms and carrying the attachment member as described. 60
- In testimony whereof, I affix my signature. 70
